GRINDING WHEEL DRESSER

Ernest A. Overstedt, Detroit, Mich., assignor to
 Louella May Dalzen, William Russel Dalzen,
 and Frederick Roy Dalzen, trustees, Dalzen
 Trust, Detroit, Mich.

Application August 9, 1944, Serial No. 548,701

12 Claims. (Cl. 125—11)

1

This invention relates to dressers for grinding wheels and more particularly to a thread grinding wheel dresser. The present invention provides a dresser for the two flanks of a grinding wheel as well as the top peripheral edge thereof.

It is the object of the present invention to provide a dressing mechanism employing a plurality of dressing diamonds adapted to dress the grinding wheel flanks from 15° to 90° included angle, and the top edge of the wheel from a flat to an angle of approximately 5° for a sloping root of thread.

It is the further object herein to provide a plurality of separately supported pivotally mounted dressing diamonds each adapted to progressively sweep one of the grinding wheel edges first in one direction and then the other.

It is the further object of this invention to provide means for slidably supporting the dresser housing with respect to the grinding wheel together with means for effecting intermittent regular adjustments of the dresser relative to said wheel.

Further objects will be seen in the various arrangements of elements and their combinations forming a part of said dresser as set out in the following specification and claims in connection with the appended drawings of which—

Fig. 1 is a front elevational view of the wheel dresser.

Fig. 2 is an elevational section of line 2—2 of Fig. 1.

Fig. 3 is a right end elevational view thereof.

Fig. 4 is a plan view thereof.

Fig. 5 is an elevational section on line 5—5 of Fig. 2.

Fig. 6 is an elevational section on line 6—6 of Fig. 4.

It will be understood that the above figures are merely illustrations of a preferable embodiment of the invention, and other embodiments are contemplated within the scope of the invention as set out in the accompanying claims.

In the drawings, the grinding wheel dresser consists of housing 11 with removable front plate 12 as shown in Fig. 1. In Fig. 4 parallel spaced ball tracks 13 are shown joined to housing 11, and adapted for vertical adjustments relative to corresponding spaced adjustable tracks 14 forming

2

ing a part of vertical slide 15, with spacer carried balls 16 interposed between said tracks.

Vertical slide screw 17 shown in Fig. 6 supported by housing 11 with bushing 18 interposed, 5 threadably engages nut 34 secured within vertical slide 15 whereby rotation of screw 17 effects vertical adjustments of housing 11 relative to said vertical slide.

Said slide is further adjustably carried by supporting bracket 19 by means of manually adjustable screw 20 rotatably carried by said bracket and threadably engaging vertical slide 15.

The latter slidably engages said bracket by the dovetail connection 21 with vertical slide gib 22 interposed and with gib adjusting screw 23 for taking up any slack therebetween, as shown in Fig. 4.

Bracket 19 which thus adjustably carries dresser housing 11, though broken away in Fig. 20 4, is adapted for attachment to the grinding wheel supporting head not shown, of for instance, a thread grinding machine.

Thus while said bracket moves together with feed movements of the grinding wheel yet vertical adjustments of the dresser housing are provided relatively to said grinding wheel to compensate for changes in wheel diameter due to wear and to dressing of the peripheral edges thereof.

30 Dresser housing feeding

Housing 11 is adapted to manual feeding relative to the grinding wheel by means of ratchet wheel shaft 24 rotatively mounted upon housing 11 within bushings 25 therein. Hand wheel 26 on one end of said shaft permits manual rotation thereof as well as of bevel gear 27 at its other end which is in mesh with corresponding bevel gear 28 secured upon vertical slide screw 17. Thus actuation of said hand wheel effects vertical adjustments of dresser housing 11 with respect to vertical slide 15, as well as with respect to grinding wheel 29.

Housing 11 is also adapted to accurate feed 45 adjustments by means of electrically actuated solenoid 30 best shown in Figs. 3 and 4. Link 31 inter-connects said solenoid and feed ratchet lever 32 by pins 33; while said lever is pivotally mounted upon ratchet wheel collar 34 forming a part of ratchet wheel 35.

The latter keyed at 36 to shaft 24 is intermittently actuated by pawl 37 in Fig. 3 pivotally carried by stud 38 extending from adjacent the end of lever 32 as shown in Fig. 1. Fig. 3 shows compression spring 39 joined to the end of pawl 37 and with its other end secured to the end of lever 32 for resiliently maintaining pawl 37 in engagement with ratchet wheel 35.

A second coil spring 40 is secured at one end at 41 to lever 32 while the other end is anchored at 42 to dresser housing 11, whereby said lever is resiliently tilted counter-clockwise. On actuation of solenoid 30 by a suitable hand switch, link 31 is projected downwardly effecting a clockwise pivotal movement of lever 32 and a corresponding translatory movement of pawl 37 to the right resulting in rotary movement of ratchet 35 and shaft 24.

Thus by actuation of solenoid 30 accurate and regular adjustments of the dresser housing may be effected relative to grinding wheel 29. Adjustable stop 43 shown in Figs. 1 and 3 adjustably supported by stud 44 on housing 11, is adapted to act as a stop for ratchet lever 32 limiting the resilient return movement counterclockwise thereof. When set as shown in Fig. 1 surface 45 is engaged by said lever permitting only enough return of pawl 37 so that only one ratchet tooth is passed thereby. Consequently actuation of solenoid 30 will result in a one-thousandth of an inch feed of dresser housing 11.

With stop 43 adjusted angularly clockwise it is seen that lever 32 can return for engagement with stop surface 46 permitting pawl 37 to pass over two teeth of ratchet wheel 35 so that upon the next actuation of said pawl the dresser housing feed will be two-thousandths of an inch.

Stop plunger 47 in Fig. 3 is resiliently urged by adjustable spring 48 into cooperative engagement with stop 43 within either opening 49 or 50 Fig. 1 for maintaining said stop in either of the two adjustments referred to.

Dresser feeding as above described may be thus effected for either successive one-thousandth of an inch feed or successive two-thousandths of an inch feed upon each actuation of solenoid 30 accompanied by downward movement of link 31. It is understood, however, that other adjustments are possible merely by changing stop 43 and its surfaces. The important feature herein resides in the fact that the return sweep of pawl 37 over ratchet wheel 35 is effectively regulated so that one or two teeth are encompassed by said pawl when actuated by lever 32.

Diamond dressing mechanism

For actuating the dressing mechanism a constant speed electric motor 51 is employed secured within dresser housing 11 as shown in Figs. 1, 3 and 4. This motor is preferably a gear reduction motor with an output of two to four revolutions per minute. It is contemplated, however, that any other type of motor would also be suitable. Rotatable output shaft 52, Fig. 1, has a crank 53 thereon carrying an off center sleeve 54, Fig. 3, upon which the upper end of connecting rod 55 is pivotally secured.

Sleeve 56 secured to pivotal operating arm 57 is pivotally joined to the lower end of connecting rod 55. Thus a single rotation of crank 53 on motor 51 effects a reciprocable arcuate movement of operating arm 57. Arcuately reciprocable arm 57 is joined to the diamond arms driving disc 58 by key 59 as shown in Fig. 2, with spring 60 interposed therebetween.

Shaft 61 secured to cover plate 12 by threaded nut 62, extends through said plate providing a support for driving disc 58 upon which it is reciprocably and arcuately journaled. Collar 63 provisioned on the end of arm 57 threadably engages shaft 61 and is secured thereby by set screw 64. Thus reciprocable arcuate movements are imparted to diamond arms driving disc 58.

Referring to Fig. 2 bracket 65 for the top diamond arm is carried upon the inner dovetail surface 66 of cover plate 12 which is arcuate in form Fig. 5 to correspond with arcuate adjustment slot 67, Fig. 1, formed therein. Arcuate clamp 68 interposed between cover plate 12 and bracket 65 is employed together with clamp screw 69 for securing said bracket either in a vertical position or in an adjusted angular position relative to plate 12.

Setting plug 70 secured to bracket 65 extends outwardly through arcuate slot 67 providing means for accurately indicating the arcuate position of said bracket.

Hollow bracket 65 with cover plate 71 has secured therein bushing 72 through which is rotatably journaled diamond arm carrying shaft 73. Plate 74 supports shaft 73 with connecting screw 75, there being a coiled spring interposed between said bracket and shaft supporting plate 74.

Top diamond carrying arm 76 is secured upon the lower end of rotatable shaft 73 with washer 77 interposed between said arm and bushing 72. Head 78 on the end of arm 76 has a transverse opening for adjustably retaining diamond holder 79 secured therein by set screw 80, there being a suitable diamond edge 81 upon the lower end of said holder.

The opposite end of arm 76 is bifurcated at 82 (only one of said bifurcations appearing in the section in Fig. 2) for receiving spherical ball member 83 upon the inner end of drive pin 84. The latter projects through a corresponding opening in reciprocable operating disc 58 and is secured thereto by nut 85.

By means of ball 83 a universal connection is effected between reciprocable operating disc 58 and the top diamond arm 76, whereby an arcuate reciprocable movement of operating disc 58 effects a corresponding arcuate reciprocable movement of the top diamond arm 76 and its supporting pivotal shaft 73. In turn an arcuate reciprocable sweeping movement of diamond 81 is effected with respect to the top edge of the grinding wheel sought to be dressed, as for instance, grinding wheel 29 in Fig. 5.

As above explained bracket 65 is angularly adjustable, changing the angle of sweep of diamond 81. However such adjustment in no way affects the arcuate movement of diamond arm 76 because of the universal ball connection between said diamond arm and the driving disc 58.

As shown in Fig. 5 a separately supported right hand diamond arm 86 is shown pivotally supported from bracket 87 by a suitable shaft carried thereby in the manner described in detail with respect to bracket 65 in Fig. 2.

Corresponding clamp screws 69 permit arcuate angular adjustments of bracket 87 with respect to arcuate dovetail slide 66 formed upon the back of cover plate 12. Similarly a setting plug 88 is secured to bracket 87 and projects outwardly through corresponding arcuate adjustment opening 89 in cover plate 12, Fig. 1.

Right diamond arm 86 with head 90 at one end adjustably supports diamond holder 91 with its diamond end 92 which is adapted to reciprocable

sweeping movement relative to one of the inclined edges of grinding wheel 29. It is understood that regardless of the angular adjustment of bracket 87 the sweeping movement of diamond 92 is always in a plane perpendicular to the central axis of said bracket.

As above described in detail, the inner end of diamond arm 86 is likewise bifurcated for receiving ball member 93 on the inner end of drive pin 94, shown in Fig. 1, but which is similar to drive pin 84 shown in Fig. 2.

Drive pin 94 projects through a corresponding opening in cover plate 12, Fig. 1, and is secured to reciprocable driving disc 58 by nut 95. Similarly, by the universal connection between reciprocable driving disc 58 and right diamond arm 86 it is seen regardless of the angular adjustment of bracket 87, that arcuate reciprocable movement of driving disc 58 effects a corresponding planular arcuate reciprocable movement of right diamond arm 86 as well as diamond 92 carried thereby.

Fig. 5 also shows a corresponding separately supported left hand diamond arm 93' pivotally supported by bracket 94 by a suitable shaft carried thereby as above described.

Corresponding clamp screws 69 permit arcuate angular adjustments of bracket 94 with respect to arcuate dovetail slide 66 formed upon the back of cover plate 12. Similarly setting plug 95, Fig. 1, is secured to bracket 94 and projects outwardly through corresponding arcuate adjustment opening 96 in cover plate 12.

Left diamond arm 93' with head 97 at one end adjustably supports diamond holder 98 with its diamond end 99 which is adapted to reciprocable planular sweeping movement relative to the other inclined edge of grinding wheel 29.

The inner end of diamond arm 93' is likewise bifurcated for receiving ball member 100 on the inner end of drive pin 101, shown in Fig. 1, but which is similar to drive pin 84 shown in Fig. 2. Drive pin 101 projects through a corresponding opening in cover plate 12 and is secured to reciprocable driving disc 58 by nut 102.

Similarly by the universal connection between driving disc 58 and left diamond arm 93' it is seen, regardless of the angular adjustment of bracket 94, that arcuate reciprocable movement of driving disc 58 effects a corresponding planular arcuate reciprocable movement of left diamond arm 93' as well as diamond 99 carried thereby.

From the above it is seen that arcuately reciprocable diamond arm driving disc 58 has adjustably secured thereto the three diamond arm drive pins 84, 94, and 101 respectively secured by nuts 85, 95 and 102.

All of these pins project inwardly through the semi-circular opening 103 in cover plate 12 terminating respectively in the three spherical members 83, 93 and 100 shown in dotted lines in Fig. 5.

Each of said members respectively joins the three diamond carrying pivotal arms 76, 86 and 93' being inserted within the corresponding bifurcations in their ends.

Thus the arcuate reciprocable movement of driving disc 58 is adapted to effect corresponding reciprocable movements of each of the diamond carrying arms. By virtue of the separate universal driving connections between said disc and each of said arms it is seen that the arcuate reciprocable movement of said disc effects separate planular reciprocal sweeping movements of each of said diamond carrying arms with respect to one of the edges of grinding wheel 29.

It will be noted as each of said arms is pivotally

supported from the adjustable brackets 65, 87 and 94 by the pivotal shafts therein, that the movements of said arms regardless of the angular adjustment of their supports is limited to reciprocable planular movements perpendicular to the axes of said brackets.

Consequently sweeping reciprocable planular movements of each of said diamonds 81, 92 and 99 are effected relative to the three peripheral surfaces of grinding wheel 29.

Because of the rocking movement of driving disc 58 it is seen that diamond 92 engages the wheel at its lowest peripheral point sweeping up and diamond 81 engages the left top edge of the wheel 29, viewing Fig. 5, sweeping to the right. At the same time diamond 99 engages the wheel at its top edge and sweeps angularly downward. On the return arcuate movement of disc 58, the reverse is true with each of said diamonds 99, 81 and 92 simultaneously sweeping over the surfaces of the grinding wheel corresponding thereto.

Referring to Figs. 1, 3 and 4, a limit switch case 104 is shown secured at 105 upon the front of motor 51 above crank 53 rotated thereby. Limit switch 106 provisioned within case 104, as shown in Fig. 3, has a central actuating means 107 for said switch which depends downwardly through bottom cover plate 108. Said switch controls by suitable wiring, not shown, stopping of motor 51 governing the dressing operation. In the lowest position of actuating means 107, and when released to assume that position, switch 106 permits operation of said motor. However with means 107 elevated the switch stops the motor. Crank 53 has a central projecting switch actuating means 109 adapted to operably engage switch actuating means 107 each time said crank completes a revolution. Thus on one revolution of crank 53 one reciprocable sweeping movement of the dressing diamonds is effected and the motor is then stopped as crank means 109 engages switch actuating means 107 projecting the same upwardly.

It is understood that motor 51 can be again restarted for another dressing operation by a suitable switch independent of limit switch 106. Naturally restarting of motor 51 effects a release of switch actuating means 107. Consequently it is seen that the sole purpose of limit switch 106 is to stop motor 51 at the end of one revolution thereof.

Again referring to Fig. 1 stationary setting plugs 110 are shown projecting outwardly from cover plate 12. These plugs provide accurate measuring points for obtaining accurate adjustments of any or all of diamond arm bracket adjustment plugs 95, 10 and 88.

Having described my invention reference should now be had to the claims which follow for determining the scope thereof.

I claim:

1. A grinding wheel dresser comprising a housing, a plurality of separately mounted diamond supporting means pivoted thereon, each adapted to sweeping dressing movements relative to one of the peripheral edges of said grinding wheel, a reciprocable disc on said housing universally joined to each of said supporting means for effecting alternate clockwise pivotal movements thereof and reversed alternate counter-clockwise pivotal movements thereof, and reciprocal means pivotally joined to said disc.

2. A grinding wheel dresser comprising a housing, a plurality of separately mounted angularly adjustable diamond supporting means pivoted

thereon, each adapted to sweeping dressing movements relative to one of the peripheral edges of said grinding wheel, a reciprocable disc on said housing universally joined to each of said supporting means for effecting reciprocable pivotal movements thereof, and reciprocal means pivotally joined to said disc, whereby slight substantially instantaneous reciprocal movements thereof effect a complete reciprocal dressing operation.

3. A grinding wheel dresser comprising a housing, a plurality of radially spaced separately mounted brackets thereon, diamond supporting means pivotally carried by each bracket and adapted to sweeping dressing movements relative to one of the peripheral edges of said grinding wheel, reciprocable disc on said housing universally joined to each of said supporting means for effecting reciprocable pivotal movements thereof, and reciprocal means pivotally joined to said disc and adapted on reciprocal movement thereof to effect a complete reciprocal dressing operation.

4. A grinding wheel dresser comprising a housing, a plurality of radially spaced separately mounted brackets thereon, a top diamond arm, a right hand diamond arm, and a left hand diamond arm pivotally carried by said brackets with dressing diamonds depending from the ends thereof for relative sweeping engagement with the peripheral edges of said grinding wheel, a pivotal reciprocable driving disc on said housing universally joined separately to the opposite ends of each of said diamond arms for effecting reciprocable pivotal movements thereof, and longitudinally reciprocal means pivotally joined to said disc for effecting reciprocal movement thereof, and adapted on reciprocal movement thereof to effect a complete reciprocal dressing operation.

5. A grinding wheel dresser comprising a housing, a plurality of angularly adjustable radially spaced separately mounted brackets thereon, a top diamond arm, a right hand diamond arm, and a left hand diamond arm pivotally carried by said brackets with dressing diamonds depending from the ends thereof for relative sweeping engagement with the peripheral edges of said grinding wheel, a pivotal reciprocable driving disc on said housing, and radially spaced transverse drive pins carried by said driving disc and universally joined to the opposite ends of each of said diamond arms for effecting reciprocable pivotal movements thereof.

6. A grinding wheel dresser comprising a housing, a plurality of angularly adjustable radially spaced separately mounted brackets thereon, a top diamond arm, a right hand diamond arm, and a left hand diamond arm pivotally carried by said brackets with dressing diamonds depending from the ends thereof for relative sweeping engagement with the peripheral edges of said grinding wheel, a pivotal reciprocable driving disc on said housing, radially spaced transverse drive pins carried by said driving disc and universally joined to the opposite ends of each of said diamond arms for effecting reciprocable pivotal movements thereof, and adjustment setting plugs carried by said brackets and extending outwardly through said housing.

7. A grinding wheel dresser comprising a housing, a removable cover plate thereon having an arcuate dovetail flange within said housing, a plurality of radially spaced brackets adjustably carried upon said flange, a top diamond arm, a right hand diamond arm, and a left hand diamond arm pivotally carried by said brackets with dressing diamonds depending from the ends

thereof for separate relative sweeping engagement with the peripheral edges of said grinding wheel, a reciprocable driving disc pivotally carried upon the outside of said cover plate, and radially spaced transverse drive pins carried by said disc, projecting through said cover plate, and universally joined to the opposite ends of each of said diamond arms for effecting reciprocable pivotal movements thereof.

10. 8. A grinding wheel dresser comprising a housing, a plurality of separately mounted diamond supporting means pivoted thereon, each adapted to sweeping dressing movements relative to one of the peripheral edges of said grinding wheel, pivotally reciprocable means on said housing, and radially spaced drive means carried by said reciprocal means and universally joined to each of said supporting means for effecting reciprocable pivotal movements thereof, and an actuating reciprocable connecting rod joined to said reciprocal means, whereby slight substantially instantaneous reciprocal movements of said pivotal means effect a complete reciprocal dressing operation.

15. 9. A grinding wheel dresser comprising a housing, a plurality of separately mounted diamond supporting means pivoted thereon, each adapted to sweeping dressing movements relative to one of the peripheral edges of said grinding wheel, reciprocable means on said housing, and radially spaced drive means carried by said reciprocal means and universally joined to each of said supporting means for effecting reciprocable pivotal movements thereof, an actuating reciprocable connecting rod pivotally joined at one end to said reciprocal means, and a motor driven crank eccentrically and pivotally joined to the other end of said connecting rod.

20. 10. A grinding wheel dresser comprising a housing, a plurality of separately mounted diamond supporting means pivoted thereon each adapted to sweeping dressing movements relative to one of the peripheral edges of said grinding wheel, reciprocable means on said housing, and radially spaced drive means carried by said reciprocal means and universally joined to each of said supporting means for effecting reciprocable pivotal movements thereof, an actuating reciprocable connecting rod pivotally joined at one end to said reciprocal means, a motor driven crank eccentrically and pivotally joined to the other end of said connecting rod, and a motor switch actuated by said crank for limiting the same to one revolution.

25. 11. A grinding wheel dresser comprising a housing, a plurality of separately mounted diamond supporting means pivoted thereon, each adapted to sweeping dressing movements relative to one of the peripheral edges of said grinding wheel, reciprocable means on said housing, radially spaced drive means carried by said reciprocal means and universally joined to each of said supporting means for effecting reciprocable pivotal movements thereof, an electric motor on said housing, a rotatable crank driven thereby, means interconnecting said reciprocable means and said crank, and a motor switch actuated by said crank for limiting the same to one revolution.

30. 12. A grinding wheel dresser comprising a housing, rotatable threaded means carried by said housing for effecting adjustments of said housing relative to said grinding wheel, a rotatable shaft operably joined to said threaded

means, a ratchet wheel on said shaft, a pivotal resiliently retractable feed ratchet lever carrying a pivotal pawl, an adjustable feed stop on said housing for limiting the extent or retraction of said lever at one end thereof, and an electrically actuated solenoid with the movable member therein joined to the other end of said lever.
